(57) **CLAIM**

The ornamental design for a scale, as shown and described.

DESCRIPTION

FIG. 1 is a top perspective view of a scale showing my new design;

FIG. 2 is a bottom perspective view thereof;

FIG. 3 is left side view thereof;

FIG. 4 is right side view thereof;

FIG. 5 is front view thereof;

FIG. 6 is a back view thereof;

FIG. 7 is a top view thereof; and,

FIG. 8 is a bottom view thereof.

Broken lines illustrate portions of the scale and/or environmental subject matter that form no part of the claimed design.
